UNITED STATES PATENT OFFICE.

JOHN F. SCHYLANDER, OF CHICAGO, ILLINOIS.

LUBRICATOR.

Application filed October 23, 1924. Serial No. 745,412.

My invention belongs to that general class of devices known as lubricators, and relates more particularly to a lubricator or oil cup particularly adapted for use on vehicles such as automobiles or the like, although the same may be used wherever found satisfactory. The invention has among its objects the production of a lubricator of the kind described which is simple, 10 convenient, compact, attractive, efficient and satisfactory for use wherever found applicable. It has among its further objects the production of a force feed lubricator which may be easily manipulated as desired. Many 15 other objects and advantages of the construction herein shown and described will be obvious to those skilled in the art from the disclosures herein given.

To this end my invention consists in the 20 novel construction, arrangement and combination and parts herein shown and described, and more particularly pointed out in the claims.

In the drawings, wherein like reference 25 characters indicate like or corresponding parts:

Fig. 1 is a sectional view through my improved type of lubricator;

Fig. 2 is a sectional view taken substantially 30 on line 2—2 of Fig. 1; and

Fig. 3 is a sectional view of a portion of the lubricator, illustrating a slightly modified top construction.

Referring to the drawings, in which the 35 preferred embodiment of the invention is shown, 1 represents a shell or container of the desired size, shape and material, provided with a stem or shank 2 arranged for attachment to the part to be lubricated, for 40 example it may be threaded as shown, and having a discharge port or outlet 3 at the end. The shell is provided with an offset or outstanding beaded portion 4 arranged to provide a chamber or recess 5 in the cup 45 when the valve or plunger is in position. The valve or plunger consists of a cup-shaped member consisting of the bottom 7 and side walls 10 arranged to fit in the cup and slide therein, the same constituting a 50 combined plunger and valve. The plunger is provided with one or more openings 11 about the same, communicating with the space 5 and normally is maintained in the position shown in Fig. 1 by a spring 12 or 55 its equivalent.

A plate or bar 13 connected with the plunger is arranged to cooperate with the spring 12 which engages with the flange 6 or its equivalent at the top of the cup. Arranged on the cup is a cap 14 which is provided with a flange 15 at the edge and preferably depressed or offset, as indicated, at the center. Between the plate 13 and the cover plate 14 is a rod or connecting member 17, the same engaging with the supplemental spring 18 arranged on the cap. Generally I prefer to provide a gasket or washer 19, as indicated. Cap 14 may be provided with an outstanding portion 20 arranged to engage with the turned-over flange 22 on a top cover part 21, which covers the spring 18 and end of the rod 17.

The cup may be filled with oil or lubricant or other material which it is desired to feed by lifting or tilting the top and discharging thereunder into the cup and plunger. Any lubricant in chamber 5 can flow under the plunger down through and out past the outlet 3 when the plunger is so raised, lubricant also flowing through the 75 openings 11 into and filling the chamber 5. Obviously, as the plunger is lifted, this causes a suction under the plunger, tending to suck the oil from chamber 5 below so that when the plunger returns, it then 80 tends to force feed the oil below the plunger through the port 3 to the point to be lubricated. When there is sufficient oil in the cup, that is, when it does not need replenishing, the part to be lubricated may be easily lubricated by merely flipping up the cover and letting it drop back, the oil being discharged down through the port 3 as 85 previously described. This may be continued until the cup is empty, it not being necessary to put oil in the cup every time. The device is therefore particularly convenient for use on automobiles or the like. Owing to the construction of the device, it is not only possible to make the same very compact and simple, but it will be likewise noted that the same cannot be easily taken apart and tampered with, so that it is always properly assembled and cannot get out of order or become disarranged. The spring 18 is 90 designed to maintain the cover tightly seated on the casing 1, that is, it is maintained seated under tension and consequently will not rattle and be noisy. Likewise being maintained firmly in place except when 95 100 105 110

raised in operating the plunger, there is no leakage of the oil between the cup and cover when the device is subjected to jars and vibration. There is no possibility of the cup 5 being left open either through forgetfulness or because the cap or cover has been lost or mislaid.

The construction shown in Fig. 3 is substantially similar, except in this case the 10 cover plate 25 is not provided with a recess but the part 26 is formed with an upstanding chamber portion 27 in which is arranged a spring 29 which bears against the head 30 on the rod 28. In this particular form, it 15 is not necessary to lift the cap as merely lifting the rod 28 will cause the valve to be opened. This type of device may be refilled or the oil replenished by lifting the 20 cap similar to the other construction mentioned. In this form the cover is always maintained seated except when lifted to operate the plunger.

In both constructions, the part to be lubricated is efficiently lubricated, due to the 25 pressure on the oil caused by the return of the plunger. The device may be operated without difficulty and without soiling the hands. When applied to an automobile, it 30 is a comparatively easy matter to go over the car and merely flip up the covers or lift on the head 30, using a screw driver or the like, and the automobile may be efficiently lubricated in but a few moments' time. There is nothing to rattle or work loose, or 35 to become mislaid.

Having thus described my invention, it is obvious that various immaterial modifications may be made in the same without departing from the spirit of my invention; 40 hence I do not wish to be understood as limiting myself to the exact form, construction, arrangement and combination of parts herein shown and described or uses mentioned.

45 What I claim as new and desire to secure by Letters Patent is:

1. In a device of the kind described and in combination, a cup-shaped casing provided with an outlet, a cup-shaped plunger valve arranged within the member, means for manually lifting said plunger valve to permit the flow of fluid in the casing to said outlet, and resilient means between the upper end of the casing and plunger valve for normally maintaining the plunger valve in closed position.

2. In a device of the kind described and in combination, a casing member provided with a shank and with a discharge port 60 therein, said casing provided with an outwardly extending bead at a point above the shank, a cup-shaped plunger arranged within the casing, said plunger provided with openings in the walls thereof communicating with the space formed by said bead,

means for retrieving the plunger in the casing, and means for advancing the plunger in the casing.

3. In a device of the kind described and in combination, a casing member provided with a shank and with a discharge port therein, said casing provided with an outwardly extending bead at a point above the shank, a cup-shaped plunger valve above said discharge port arranged within the casing, said 70 plunger provided with openings in the walls thereof communicating with the space formed by said bead, a cover over said casing, a rod connecting said plunger and cover, said rod yieldingly secured to the 75 cover, and a spring arranged to normally maintain the plunger valve in closed position.

4. In a device of the kind described and in combination, a casing, a plunger of cup 80 shape arranged therein and dividing the casing into an upper and a lower chamber, said casing formed to provide a valve seat at the closed end of the plunger and with a discharge opening leading from the lower 85 chamber, said casing having an outwardly extending beaded portion at and about the walls of the cup-shaped plunger and providing a third chamber thereabout, said 90 plunger having ports connecting the interior of the plunger with said third chamber, a closure for said casing, a rod connected with said closure and with said plunger for controlling the same and a spring arranged to 95 normally maintain said plunger on its seat.

5. In a device of the kind described and in combination, a casing, a plunger of cup shape arranged therein and dividing the casing into upper and lower chambers, said 100 casing formed to provide a valve seat for the plunger and with a discharge port from the lower chamber, said casing having an outwardly extending beaded portion at and about the walls of the cup-shaped plunger and providing a third chamber thereabout, said plunger having ports connecting the interior 105 of the plunger with said third chamber, a closure for said casing, a rod yieldably connected with said closure and with said plunger for controlling the same, and a compression spring arranged to normally maintain said plunger on its seat, said spring 110 abutting the plunger and engaging the top edge of the casing.

6. In a device of the kind described and in combination, a casing, a plunger valve of cup shape arranged therein and dividing the casing into upper and lower chambers, said 115 casing formed to provide a valve seat for the plunger valve and with a discharge port from the lower chamber, the casing having an outwardly extending beaded portion about the cup-shaped plunger valve providing a third chamber thereabout, said plunger having ports communicating with said third 120 125 130

chamber, a closure for said casing, a rod extending through said closure and yieldably connected therewith and connected with said plunger for controlling the same, and a spring arranged between the closure and plunger for maintaining said plunger on its seat.

7. A device of the kind described comprising a casing, a plunger dividing the casing into three chambers, one chamber being above the plunger, one chamber below the plunger, and an outer chamber surrounding the exterior of the plunger, a closure

member adapted to seat on the casing to close the upper chamber, a discharge port 15 in the casing wall communicating with the lower chamber, a port in the plunger forming communication between the upper chamber and the outer chamber, and yielding means for holding the plunger in position 20 wherein it prevents the flow of liquid to the lower chamber which communicates with the discharge port in the casing.

In testimony whereof, I have hereunto signed my name.

JOHN F. SCHYLANDER.
